Primary Examiner — Mark A Goodwin

(74) *Attorney, Agent, or Firm* — MLO, a professional corp.

(57) **CLAIM**

The ornamental design for an escutcheon, as shown and described.

DESCRIPTION

FIG. 1 is a perspective view of an escutcheon showing my new design;

FIG. 2 is a front elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The rear elevational view forms no part of the claimed design and is omitted.

The broken lines are for illustrating portions of the article which form no part of the claimed design.

1 Claim, 4 Drawing Sheets
